REMOTE-CONTROLLED AUTOMATIC TELEPHONE FOR LOUD TRAFFIC

Otto Tschumi, Soleure, Switzerland, assignor to
Autophon Aktiengesellschaft, Soleure, Switzerland, a joint-stock company of Switzerland

Application May 12, 1944, Serial No. 535,299
In Switzerland December 21, 1942

4 Claims. (Cl. 179—81)

1

This invention relates to remote-controlled automatic announcing telephone installations.

Heretofore, if the loud-speaker in a remote-controlled automatic announcing telephone installation was used both for transmitting ordinary calls and for special signals which are not initiated by operating the connecting means of the manual exchange, special additional means were necessary for changing over the telephone from the special use conditions to normal operating conditions. Besides this, in known installations it was not possible during the special use to determine whether the subscriber in question was called in the normal manner or not.

The remote-controlled automatic telephone according to the invention is characterized in that during use for special purposes, the calling conditions for normal traffic remain established.

The installation according to the invention comprises a telephone station with an amplifier and a transducer, which latter is applicable as a loudspeaker and a microphone, whereby the amplifier and the transducer may be used not only for receiving and transmitting ordinary telephonic conversations, but also for receiving and transmitting other signals. When reference is made to "normal use," "normal operating conditions" or "normal operation," this means use for receiving or transmitting telephonic conversations, or telephone connection, or in general the use of the telephone station for the reception and transmission of telephonic conversations.

As this reception and transmission of telephonic conversations is the main object of the telephone installations according to the invention, it is referred to generally in the specification as "normal" (i. e. the usual way of using this installation). In contrast thereto is the "special" use, (i. e. other or additional use) of the telephone station or the amplifier and the loudspeaker of said station, that is, the use for the reception and possibly also for the transmission of other signals, such as, for instance, high-frequency, voice modulated signals, or for the reception of wire broadcasting signals, or for the transmission of phonograph records, or, finally, for the connection to another telephone line in addition to and differing from the ordinary exchange line. The use of the telephone station for the reception of such signals which are not incoming on the ordinary exchange line, has been called "special use" (i. e., another, additional use), the rendering audible of the signals received in this way "special reproductions," the corresponding reception "special receiving," and the object

2

of using the telephone station for these purposes and, in addition thereto, possibly also for connection to another, separate line or a dictaphone "special purpose." The "special operating conditions" are accordingly the switch positions and operating conditions which correspond to this "special use."

Thus the main purpose or object of the apparatus in accordance with the invention is the exchange of telephonic conversations on an exchange line. Another, additional purpose of the telephone installation is the reception and possibly the transmission as well as the amplification of signals which are independent from said ordinary telephonic conversations.

If desired, the arrangement may be chosen so that, on a call, the normal position of the stations is, at least during the normal use, automatically established, so that additional switch devices for the interruption of the special use and the establishment of the normal operating conditions are no longer necessary. Furthermore, measures may be taken allowing an outgoing connection to be made and a conversation to be had without the special use circuit being manually disconnected. This disconnection takes place automatically upon the establishment of connections with the automatic main station.

The accompanying drawings illustrate, by way of example, one embodiment of the invention and different applications of the same.

Fig. 1 is a diagram of this embodiment;

Fig. 2 shows the application of the circuit to utilization for the reception and possibly also for the transmission of other signals such, for instance, as high frequency voice modulated signals;

Fig. 3 shows the utilization of the circuit for the reception of wire broadcasting signals;

Fig. 4 shows the circuit utilized for the transmission of phonograph records and the like; and

Fig. 5 shows the connection of the subscriber's station to another telephone line in addition to the ordinary exchange line.

In Fig. 1, EW designates a transducer capable of operating either as a transmitter or a receiver. According to the manner of operation this transducer is connected with either the input transformer EV or the output transformer AV of the amplifier V. The corresponding change-over switches are designated by the characters u_1 and u_2 . The two contacts u_1 and u_2 , actuated by a double wound relay U_2 , the windings of which are designated by " $U\Omega$ " (high ohmic) and " $U\omega$ " (low ohmic), are operable so as to be reversed

from the position shown in a full line to that shown in a broken line, when either of said windings is traversed by current. The amplifier V is turned on by closing a contact e_1/u_3 to connect the amplifier with a power source P. The contact e_1/u_3 is closed when either one of the windings U_Ω or U_ω is energized and is also closed by the energizing of a relay winding E. The winding E also controls contacts e_2 and e_3 . When the winding E is energized the contacts e_2 and e_3 are reversed from the positions shown in full lines to those shown in broken lines respectively. With the aid of the contact e_3 the incoming side of the amplifier can be brought into connection with a terminal 1 and transformer Ue or with a terminal 2. The terminals a, b of the transformer Ue are connected with each other by an impedance coil Dr, the middle of which is connected with the impulse contact i of a conventional calling dial NS either over the condenser CI or the contact ES and the contact e_2 . The impulse contact i is grounded over a rectifier arrangement. The contact e_2 in its rest position connects the impulse contact i over the high ohmic relay U_Ω with the terminal 3, while the terminal 4 is in direct connection with the middle of the impedance coil Dr. The rectifier arrangement comprises essentially a full wave rectifier bridge consisting of four rectifier elements G_{1-4} , with connection points 5 and 6 and bridging points 7 and 8. The relay winding E, the contacts of which are designated by e_{1-3} , is connected across the points 7 and 8 and is operable by line current in either direction. The connecting point 5 is connected to a lamella of the impulse contact i of the calling dial NS whereas the counterpoint 6 is grounded. The one (8) of the two bridging points 7 and 8 is grounded over the low ohmic winding U_ω of the double wound relay U and over a switch sh, whereas the other (7) is grounded on the one hand over a resistance W3 and said contact (sh), and on the other hand connected in parallel over a pilot lamp KL connected in parallel with W3. The low resistance relay winding U_ω constitutes an element dependent on the kind and direction of current.

It may be mentioned that RW is a regulating resistance, KH an earphone, W1 a first and W2 a second ohmic resistance and, finally, sKH a switch for adjusting the earphone.

The terminals a—b, 1—4 and ER are the outgoing terminals of the installation according to the invention. The terminals a, b are connected, for a given purpose, directly or indirectly to the exchange line designated A, B (Figs. 2—5), whereas the terminals 1—4 and ER are connected, according to the purpose, to the corresponding terminals of auxiliary apparatus for the special or additional purposes defined above. In addition to these terminals, there is an external connection to a power source P for the heater current of the amplifier V.

The calling dial NS is an ordinary calling dial as used in automatic telephony. With the calling dial in rest position, the short-circuit contact k is open and the impulse contact i is closed, whereas during the winding up of the calling dial and its return, the short-circuited contact k is closed. The impulse contact i remains closed during the winding up of the dial, and during the returning of the dial opens as many times as corresponds to the number selected. With regard to the object of the invention, the calling dial is essential only in so far as, with the beginning of the selecting process, that is, on starting the winding up of the dial and the corresponding closing of the

short circuit contact k, the potential existing on the two exchange lines A, B, is applied to the closed impulse contact i to the input point 5 of the rectifier arrangement and the relay winding U_Ω is thereby bypassed.

The manner of operation of the device shown is as follows:

If the device is to be connected for receiving in a special use, the terminals 3 and 4 are short-circuited by the subscriber. The high ohmic relay U_Ω is thereby inserted into the circuit, resulting in the operation of the switches u_1 , u_2 and u_3 . Owing to the low amperage caused by the high resistance, the current flowing in the relay E is too small to bring the latter into action. The contacts e_1 , e_2 and e_3 thus remain in their rest position. Consequently, e_2 remains in the position shown in solid lines, and results in continued operation of relay U_Ω , while contact e_3 switches the audio-frequency signals of the special signals arriving through the terminal 2 to the amplifier. On the other hand, by reversing the contacts u_1 and u_2 the subscriber device is brought into receiving condition so that the audio-frequency signals arriving through the terminal 2 can be heard in the transducer EW. This, however, is possible only since the amplifier is energized owing to the operation of switch u_3 and in spite of the fact that contact e_1 remains in inoperative rest position. In this way, the device is adjusted for receiving the special signals. The calling conditions of the station are assured in that a signal coming in through the terminals a, b goes over the condenser CI to the rectifier arrangement and there-by also to relay E. Owing to this additional current relay E actuates its contacts disconnecting both the incoming signals of the special use and the high ohmic resistance of relay U_Ω . By disconnecting this high ohmic resistance at the contact e_2 the current in relay E is further increased, so that, even after the calling signals have ceased, the station is in its normal operating condition.

If the normal operation ceases, and the subscriber wishes to be able to take up the special use at once, he takes care that the contacts 3 and 4 remain short-circuited even during the normal operation, which results in the fact that, after termination of this normal operation and the resulting reduction of the direct current in the relay E, the contacts of the latter return to rest position. The high ohmic resistance of relay U_Ω is again inserted into the circuit by contact e_2 (the amplifier being adjusted to hearing condition) and contact e_3 leads the signals of the special service again to the amplifier. If, after the normal operation has ceased, the subscriber no longer wishes to maintain the special operating conditions, he separates the terminals 3 and 4 whereby the contacts e_{1-3} return to their rest position, the amplifier V, however, remains disconnected owing to the non-operation of relay U.

If, during a special use, the subscriber is desirous of carrying out a normal operation, the special use need not be interrupted, but the necessary connection can be established as if there were no special use actually at work. By the operation of the calling dial and the resulting short-circuiting of the sparking contact k, the potential of the terminals a, b is directly connected to the rectifier arrangement, while the high ohmic resistance in relay U_Ω is bridged over. In this way, the amperage E is increased to such a degree that this relay E comes into action and establishes normal operating conditions.

Figs. 2—5 show the installation according to

Fig. 1 in its connection to auxiliary apparatus adapted for various other (special) purposes, whereby, for the sake of simplicity, said installation according to Fig. 1 is shown in Figs. 2-5 in broken lines only as a square which is designated EE, and only the outgoing terminals are designated more precisely. In Fig. 2, for instance, it is to be seen that the terminals 2-4 as well as *a*, *b* and ER are connected to terminals 21, 31, 41, *a*₁, *b*₁ and ER₁ of the auxiliary apparatus HG corresponding to the special (or additional) purpose in question. As the terminal *t* is not used for this particular purpose, it is represented as an unconnected terminal. This auxiliary apparatus consists essentially of a schematically represented high frequency amplifier HV and a transformer UeV as well as of a key T for short-circuiting the terminals 3 and 4 to establish receiving conditions.

As indicated above, the special (or additional) purpose in the case of Fig. 2 consists in the reproduction of audio frequency modulated high frequency signals which, just as the ordinary call, are received over the line A, B and which have nothing to do with the normal purpose which consists in receiving and transmitting voice signals during a conversation. As has already been pointed out, the object of the invention consists in adjusting an installation, as shown in Fig. 1, alternatively for the ordinary transmission of voice signals and also for receiving other signals. These other signals are, in the embodiment of Fig. 2, high frequency signals which likewise are conveyed to the subscriber on exchange line A, B, whereby the adjustment of the condensers C and the inductance coils D causes the high frequency signals to be directed over the condensers C permitting the passage of high frequency currents to the auxiliary apparatus HG or its high frequency amplifier HV, and the low frequency voice current to be directed over the coils D direct to the receiving station EE.

The ground terminal ER is connected to a like terminal ER₁ of the auxiliary apparatus HG and is grounded.

By →Z it is indicated in Figs. 2-5 that the line A and B is the exchange line coming from the central station Z.

In accordance with the special use of Fig. 2 an audio frequency modulated high frequency signal is received over the terminals *a*, *b* and over the transformer UeV of high-frequency amplifier HV, after the called subscriber has established receiving conditions by operating the key T.

If, during the special use, the receiving station is now called by the main station, the call, owing to the device according to the invention, is received and the connection at once established.

In Fig. 3, besides the schematically shown receiving station EE, an auxiliary apparatus TZ is shown which permits, as a further, additional purpose, receiving wire broadcasting signals in addition to the ordinary voice signals of the telephone traffic. In this embodiment, the terminals 1 and 2 are not used and may, therefore, be short-circuited. The terminals 3 and 4 of the receiving station EE are to be connected to the corresponding terminals 32, 42 of the auxiliary apparatus TZ and can be short-circuited by the key T. The aim of this short-circuiting has already been described in connection with Figs. 1 and 2. The terminals *a*, *b* are connected to the corresponding terminals *a*₂ and *b*₂ of the auxiliary apparatus, which terminals *a*₂ and *b*₂ of said apparatus are brought partly (*a*₂) direct and partly

(*b*₂) over a selecting key WT to the output terminals *a*₃ and *b*₃ to which the exchange line A, B is connected. Here, again, ER is the ground terminal which is connected to a like terminal (ER₂) of the auxiliary apparatus TZ, whereby the selecting key WT may be grounded temporarily by known means (not shown) in order to change the program, which change is made at the central station Z.

10 The condition for broadcast receiving is established by closing the key T while with the selecting key WT a program-selecting switch can be changed over by the disconnection and direct grounding of the wire B. Here, too, a call coming from the main station Z is received automatically and the connection with the main station Z established. At the same time the telephone broadcasting is disconnected from the receiver.

In Fig. 4, the additional or special purpose 20 consists in the reproduction of phonograph records or magnetic recordings. The auxiliary apparatus is designated by WE and consists substantially only of a switch Sr and the connecting terminals 23, 33, 43, 9 and 10. One of the

25 poles of the pick-up of a phonograph or the sound head of a magnetic recorder (not shown) is connected to the corresponding terminals 3 and 4 of the installation EE. To the terminals 9 and 10 is connected the driving motor of a phonograph or the steel tape of a magnetic recorder (not shown). Of the other terminals of the installation, terminal ER is grounded, whereas to the terminals *a* and *b* is connected the exchange line A, B, coming from the central station Z. Terminal *t* is not used. It follows from the arrangement shown in the drawing, when switch Sr is reversed, not only the circuit of a driving motor (not shown) is closed, but also the terminals 33 and 43 or 3 and 4 are short-circuited.

30 35 40 The effect thereof is that the installation EE is adjusted to this special (additional) reproduction and the signals coming in over the terminals 23 and 2 become audible in the electro-acoustic transformer EW, as shown in Fig. 1.

45 In Fig. 5, the special purpose consists in the reception of a direct second telephone communication which is independent from the "normal" or main ordinary line.

The normal (or main) communication is led-in 50 from the central station over the terminal *a*, *b*, whereas the additional communication with the installation EE is established over the line L-L. The problem solved here consists in that the receiving station EE can receive, in the indicated

55 way, communications coming from the exchange line (A, B)—normal use—and also from another, for instance, an internal line (L, L)—special use. In Fig. 5, SE designates two batteries B and B₁, a transformer AU and a key Ta, so that the emitted voice currents are transmitted to the line LL when the microphone M is controlled and simultaneously the key Ta is closed. Between the two wires of line L-L is arranged the winding S of a relay whose switch s is open in rest position.

60 65 70 75 If the Key Ta is closed in the emitting direction SE, then a circuit: battery B₁—key Ta—secondary winding of the transformer AU—line L—relay winding S and back to the second wire of the line L to battery B₁, is closed. Thereby the winding S becomes energized and the contact s, which is associated to the relay in question, is closed and short-circuits thereby the terminals 3, 4 which correspond to the terminals 3, 4 of Fig. 1. The effect obtained thereby has been described in connection with Fig. 1. With this ar-

angement it is furthermore possible to provide a special loud speaker LS for the special reception and to connect it to the line L—L. This, however, is not absolutely necessary. The terminals *a*, *b* and ER are adjusted in like manner as in the preceding examples.

The normal operating conditions require a permanent excitation of the relay E, but only for a temporary operation of relay U (for changing the speaking direction). In the case of special 10 use the conditions are in so far reversed, as relay U permanently carries current and relay E is constantly in rest position. In other words, both in normal operation and in special operation, the same relays are brought alternatively into 15 action.

Accordingly, it is clear that for this alternative operation of the relays E and U a purely mechanical snap action can be used in such a way that this latter, at the moment of the operation of relay E, releases relay U.

If, in normal operation, EW is used by the subscriber as transmitter (e. g., for dictation), the readiness to receive calls is maintained provided that the contact *e*₁—*u*₃ can be bridged-over by a manual switch.

I claim:

1. A remote control automatic telephone subscriber's station comprising a transducer, an amplifier having input and output connections from the amplifier to the transducer and to terminals for connecting the station with an exchange line, connections from the amplifier to another line differing from the exchange line, a first relay having operating contacts for reversing the input and output connections of the amplifier to control the speaking direction, a full wave rectifier bridge arrangement, connections including a condenser for connecting the rectifier bridge with the exchange line including a condenser in parallel with said first relay, a second relay connected across the rectifier bridge and responsive to current supplied by the exchange line through said condenser, said second relay having operating contacts for switching the amplifier from the connections with said other line to the connections with the exchange line.

2. A remote control automatic telephone installation comprising an amplifier, an exchange line, means for connecting the amplifier to the exchange line, two contacts controlling the speaking direction, a relay having a high ohmic winding, a first terminal providing connections with another line different from the exchange 50 line, leads from said terminal to the amplifier,

a condenser bridging the high ohmic winding, a second terminal connected to the high ohmic winding, a third terminal connected to the exchange line, a rectifier bridge arrangement comprising a full wave rectifier, a second relay having a winding which is connected across said rectifier, operating contacts associated to said second relay, and comprising a contact operable to disconnect the high-ohmic winding, and a second contact operable to disconnect the first terminal from the leads to the amplifier.

3. A remote control automatic telephone subscriber's station, comprising a receiver and transmitter assembly, connections from said assembly to an exchange circuit and to another circuit different from said exchange circuit, a full wave rectifier bridge, means including a first relay winding for connecting the rectifier bridge with the exchange line, a second relay winding connected across the rectifier bridge, the resistance of said first relay winding being so high that current supplied therethrough is insufficient to operate the second relay, operating contacts associated with the first relay controlling the speaking direction, operating contacts associated with the second relay for connecting the receiver and transmitter assembly alternatively with the exchange line on said other line, a calling dial having short-circuiting contacts connected with the exchange line and impulse contacts, and connections including said impulse contacts and a condenser in parallel with said first relay winding for connecting said rectifier bridge with the exchange line, thereby by-passing said first relay winding.

4. A circuit according to claim 3 in which operating contacts operable by both the first and the second relays are provided for connecting the receiver and transmitter assembly with 40 a power source.
